EXPANSIBLE CONTAINER FOR FLUIDS AT
LOW TEMPERATURE

Walter L. Benson, Needham, and Norman C. Dahl, Lexington, Mass., assignors, by mesne assignments, to Constock Liquid Methane Corporation, New York, N.Y., a corporation of Delaware

Filed Apr. 3, 1958, Ser. No. 726,112

6 Claims. (Cl. 220—9)

This invention relates to storing and shipping liquefied gases at low temperatures and more particularly to the storing and handling of such liquefied gases in large metal tanks which are surrounded by insulating materials.

Many types of containers suitable for handling liquids which must be maintained at relatively low temperatures are known and used. One of the most common of these is the metal tank set completely within another tank or receptacle with insulation material placed in the space between the inside metal tank and the outside receptacle. Because the inside tank is metal it possesses a coefficient of thermal expansion and hence is subject to contraction and expansion when exposed to temperature changes. The problem of expansion and contraction becomes markedly acute at the temperatures normally encountered in the handling of liquefied gases because the temperature differential between the liquefied gas temperature and normal room temperature is very great.

In the case where the inside tank designed for storing or shipping liquefied gases is completely surrounded by an insulating material, such as balsa or cellular glass for example, contraction of the tank walls when the liquefied gas is added means that the walls pull away from the insulating material leaving a void area between the outside wall of the tank and the insulation material. There are cases where it is desirable to design the inside tank, containing the liquefied gases, so that it will depend for structural support upon the insulating material and the outside wall of the receptacle surrounding the insulating material. When this is desirable it may readily be seen that a gap between the walls of the inside tank and insulating material would lead to stresses in the tank walls brought about both by the removal of the needed structural support offered by the outside receptacle and insulating material and by the pressure of the liquid load within the inner tank in addition to the pressure under which the liquid and vapor, filling the space above the liquid, might be maintained within the tank. Repetition of the cooling-warming cycle, brought about by the addition and removal of the liquefied gas, and hence of the stresses set up, after a relatively short period, may cause the inner tank to fail.

Moreover, if the inner tank containing the liquefied gas is only partially filled a large temperature gradient will exist in the gas column above the liquid level. This means that the tank walls will also exhibit a marked temperature gradient approximating the temperature gradient in the gas because of the very low thermal conductivity of metal walls at the low temperatures involved. The resulting temperature gradients introduce additional stresses in the walls which may be partially relieved by the tank design of this invention.

It would be desirable to be able to fabricate metal tanks for the storage of a cold boiling liquid in large volume wherein the tanks could be fabricated of an inner

2

shell having relatively thin metal walls which would depend upon the outside receptacle or the insulation layer for structural support, thus reducing the weight and cost of the storage or shipping tank. One way in which the tank could be made to meet these requirements is to have at least a portion of the metal tank expandable under the load and pressure conditions existing to enable deformation which would allow the walls of the tank continuously to engage the insulation layer for support.

It is, therefore, an object of this invention to provide a tank, suitable for storing and shipping liquefied gases, which may be constructed of thin metal walls, thus resulting in lower construction costs.

It is an additional object to provide receptacles, suitable for storing and shipping liquefied gases, which remain continuously in contact with insulating material surrounding them.

It is another object to provide receptacles, suitable for storing and shipping liquefied gases, which remain continuously in contact with insulating material surrounding them and which employ an insulation in combination therewith characterized by having a structural strength sufficient to maintain their mass integrity and shape under load to provide an adequate support for the inner metal tank.

It is another object to provide an inner receptacle for storing and shipping liquefied gases which depends for a portion of its structural support upon an outside receptacle. It is a further object of this invention to provide receptacles, suitable for storing and shipping liquefied gases, which are expansible under the hydrostatic load and under the pressure built up within the receptacle by the vaporization of the liquid into gas. These and other objects will appear in the following discussion which is presented with reference to the accompanying drawing in which—

Fig. 1 represents a cross-sectional view of the type of tank construction to which this invention is applicable;

Fig. 2 is a perspective view of three walls of a tank joined at a corner in accordance with this invention;

Fig. 3 is a plan view of a corner of a tank having all three walls meeting at the corner joined by the cylindrical expansion joints of this invention;

Fig. 4 is a front elevation of the corner of Fig. 3, and

Fig. 5 is a cross-sectional view of section 5—5 of Fig. 3.

By the process of this invention, a tank suitable for the storage and transportation of liquefied gases is made expandable to allow the sides of the tank to remain substantially continuously in contact with the insulation and hence to make full use of the additional structural support offered by the insulation alone or in combination with the outside receptacle. This is done, in accordance with the practice of this invention, by connecting the walls of the tank by means of cylindrical expansion joints.

In the tank of this invention, a single expansion joint is used at the edge of each plane of the tank to form the corner portion between the walls. The internal pressure exerted by the liquid and by the liquefied gas will cause deformation of the joints to relieve the stresses on the tank walls and to enable deformation sufficient to enable the tank walls to remain substantially in surface contact with the insulation layer notwithstanding the expansions or contractions which take place in the metal during changes in the temperature thereof. The tanks of this invention may be better described in detail with reference to the figures. It is preferred to make use of an expansion joint of cylindrical or curvilinear shape, as shown, but

it will be understood that expansion joints of other shapes and cross-section may be employed. When expansion

joints of such other configuration are employed, it is desirable to avoid the use of sharp corners in the connecting planes since it will be apparent that flexure for expansion and contraction of the tank will occur many times in use.

In Fig. 1 there is shown a simplified cross-sectional drawing of the general type of tank used for storing or shipping liquefied gases. The tank will be a polyhedron configuration and preferably one which is a rectangular parallelepiped. Inner tank 10, designed to contain the liquefied gas 13, is placed within a surrounding vessel 11 and insulating material 12 placed between them. Such a tank may be equipped with a filling line 21 in which is placed a pressure-regulating valve 20 to provide proper gas venting, and with a draw-off line 22 incorporating valve 23. When the sides, top and bottom of tank 10 press closely on the insulating material, tank 10 forms an integral unit with tank 11 and tank 10 may therefore be of a lighter weight, thinner construction than if this integration did not exist. When the walls of tank 10 are cooled by the introduction of the liquefied gas, they contract, if made in the conventional manner, and pull away from the insulation and destroy the necessary integration and interaction.

In a tank such as shown in Fig. 1, the surrounding vessel 11 may be eliminated where insulation 12 is of such structural material, such as cellular glass, cork or balsa wood, that it forms a strong outside receptacle. In such a case, by maintaining the tank walls 10 in contact with insulating material 12 a strong integral unit is achieved without the additional tank 11.

The manner in which the walls of the tank of this invention are made expandable is shown in Fig. 2 which illustrates how three walls 16 are joined at a corner. Three-quarter cylindrical sections 18 are welded along wall edges 19 and at their lines of intersection 17. Figs. 3 and 4 (in which like numbers refer to like elements of Fig. 2) are a plan view and a front elevation view of the corner of Fig. 2 in which three walls are joined by the expandable cylindrical joints of this invention.

In Fig. 5, two expandable walls 16 across section 5-5 of Fig. 3, are shown joined by a three-quarter cylindrical expansion joint 18 at their points of contact 19. Pressure, applied in the direction of the arrows, causes the expansion joint to become deformed, thus giving sufficient "spring" or expansion to walls 16. Likewise, when walls 16 are brought into contact with the liquefied gas at low temperature they will contract again causing the cylindrical expansion joints to deform, thus relieving the stresses of contraction in walls 16.

Although it will generally be convenient to have all of the sides, along with the top and bottom, joined by means of the cylindrical expansion joints, there may be tank designs in which less than all of the surfaces making up the tank walls will require cylindrical expansion joints. Thus, for example, if a tank were constructed so that its height/cross-sectional dimension ratio was very high, the top and bottom could be rigidly attached to the sides which in turn would be joined by the cylindrical expansion joints. Likewise, if it is possible to allow the tank to slide freely within the enclosure formed by the insulation, it would be feasible to join only two adjacent walls and the top of the tank by means of the cylindrical expansion joints. The remaining walls may then be joined by any suitable method. Thus, a number of combinations are possible, the final design considerations governing the choice made from these combinations.

The walls and cylindrical expansion joints of the tanks of this invention may conveniently be constructed of stainless steel. However, other suitable metals, such as aluminum and copper or alloys, which possess the desired structural strength and degree of resilience, may be used. When use is made of the tank for the storage or transportation of a very low boiling liquefied gas, such as in the storage or transportation of liquefied natural gas

maintained at about atmospheric pressure and a temperature of about -250° F., it is desirable to fabricate the tank of a metal such as aluminum or alloys of aluminum, or stainless or other austenitic steels which are capable of retaining their strength and flexibility at the temperature conditions existing.

The degree of flexibility, i.e., the amount of deformation in the cylindrical joint, will determine the radius of the cylinder or curvilinear section in the expansion joint. Another factor in the determination of the radius or curvature is the thickness of the material of which the expansion joint is formed and the pressure at which the tank operates. As an example, the radii may vary from 4.8 inches to 8.7 inches for stainless steel cylinders made of 0.037 inch to 0.125 inch material when the tank has an internal pressure of about 20 p.s.i.g. Generally, for a given stress and deflection, the thicker the cylinder material, the greater the radius must be. Other design factors which must be considered in determining material thickness and cylinder radius are the material used for tank construction, the degree of flexibility required, the internal pressure of the tank, overall dimensions of the tank, and the number of walls or surfaces joined in the manner of this invention. All of these factors must be balanced in the design of a tank for a particular purpose.

The cylindrical expansion joints may conveniently be die pressed, but any suitable method of forming may also be used. Although welding is usually the preferable manner of joining the walls to the cylindrical expansion joints, other suitable methods such as crimping may be used. The final tank will be so constructed as to afford a hermetically sealed container suitable for holding liquefied gas.

35 Thus, by the use of the expandable tanks of this invention, there are provided means for continuously keeping the outside of the tank walls in contact with the insulating material surrounding the tank which in turn means that thin-walled tanks may be used since the tank can be structurally supported by the insulation and the outside tank or by the insulation alone.

We claim:

1. In a tank for the storage of a liquid, the boiling point of which differs widely from the ambient temperature, comprising an inner shell housing said liquid and which is subject to noticeable expansion and contraction due to temperature change, an outer shell spaced from the inner shell to provide a confined space therebetween, and thermal insulating material between the shells, the improvement wherein said inner shell having the shape of a polyhedron is provided with an expansion joint at each of the sides of said polyhedron, each such expansion joint being in the form of a curvilinear section extending continuously throughout the lengths of the joined sides, the outer surface of said section being convex with respect to the interior of the inner shell, and the two edges of said section being hermetically sealed to the adjacent edges of the two sides which it joins, whereby the inner shell remains continuously in contact with the insulating material.

2. A tank according to claim 1 wherein said inner shell is a rectangular parallelepiped.

3. A tank according to claim 1 wherein all of the edges of the sides of said polyhedron are provided with said expansion joint.

4. A tank according to claim 1 wherein said expansion joint is in the form of a major part of a cylinder having its axis parallel to the contiguous edges of the sides which it joins.

5. A tank according to claim 4 wherein said expansion joint is in the form of a three-quartered cylinder.

6. In a tank of large capacity for the storage of a liquefied natural gas at about atmospheric pressure comprising an inner shell formed of a metal capable of retaining its ductility at the low temperature of the lique-

fied gas and which is subject to change in dimension due to expansion and contraction in response to temperature change, an outer shell surrounding the inner shell in spaced relation therewith to provide an open space in between filled with thermal insulation material, the improvement wherein said inner shell having the shape of a polyhedron is carried out with thin metal walls provided with an expansion joint at each of a plurality of the edges of the walls of said polyhedron, each such expansion joint being in the form of a curvilinear section extending continuously throughout the lengths of the joined walls, the outer surface of said section being convex with respect to the interior of the inner shell, and the two edges of said section being hermetically sealed

to the adjacent edges of the two walls which it joins and from which said edges of the two walls extend tangentially, whereby the inner shell remains continuously in contact with the insulation material and depends upon the outer shell or the insulation material layer for structural support.
